UNITED STATES PATENT OFFICE.

AARON ROSENBLUM, OF UNION HILL, NEW JERSEY.

DESIGN FOR A PICTURE FRAME.

Application filed December 3, 1924. Serial No. 11,577. Term of patent 3½ years.

To all whom it may concern:

Be it known that AARON ROSENBLUM, a citizen of the United States, and resident of Union Hill, in the county of Hudson and State of New Jersey, has invented a new, original, and ornamental Design for Picture Frames, of which the following is a specification, reference being had to the accompanying drawing, forming part thereof, in which the figure is a perspective view of a picture frame embodying my new design.

I claim:

The ornamental design for a picture frame as shown.

Signed at New York city, in the county of New York and State of New York, this 26th day of November 1924.

AARON ROSENBLUM.
